UNITED STATES PATENT OFFICE.

PHILIP E. EBRENZ, OF ST. LOUIS, MISSOURI, ASSIGNOR TO JOHN DEERE PLOW COMPANY, OF ST. LOUIS, MISSOURI, A CORPORATION.

VEHICLE-THILL.

No. 927,778.

Specification of Letters Patent.

Patented July 13, 1909.

Application filed March 18, 1909. Serial No. 484,155.

To all whom it may concern:

Be it known that I, PHILIP E. EBRENZ, a citizen of the United States of America, residing in the city of St. Louis and State of Missouri, have invented certain new and useful Improvements in Vehicle-Thills, of which the following is a full, clear, and exact description, reference being had to the accompanying drawings, forming part of this specification.

My invention relates to an improvement in vehicle thills and has for its object to render the heels and coupling members of such thills of greater strength and durability.

Figure I is a view partly in elevation and partly in longitudinal section of one of the heels of my thill. Fig. II is a rear elevation of the shaft heel shown in Fig. I. Fig. III is an enlarged view partly in rear elevation and partly in section of the coupling end of the thill heel shown attached to the coupling member that mates therewith. Fig. IV is an enlarged cross section taken on the line IV—IV Fig. II. Fig. V is an enlarged vertical section through the coupling end of the heel.

In the accompanying drawings: 1 designates the wooden heel of a vehicle thill which is shaped similar to the usual manner of shaping said heels.

2 designates a lower reinforcing and coupling iron that extends throughout the length of the heel 1 and beneath the lower end of the heel, as illustrated in Figs. I and V. This reinforcing and coupling iron is provided at its lower end with a coupling eye 3 containing a bolt hole 4.

5 designates an upper or outer reinforcing coupling iron that extends longitudinally of the heel and is curved both longitudinally and transversely to fit the contour of the heel. The reinforcing and coupling iron 5 is provided at its lower end with side wings 6 which extend forwardly at the sides of the heel and carry at their extremities eyes 7 provided with bolt holes 8 that are adapted to register with the bolt hole 4 in the eye of the lower or forward reinforcing and coupling iron 2.

50 The wings 6 of the coupling iron 5 which straddle the lower end of the thill heel and the eye 3 of the coupling iron 2 are spaced apart from each other and from said members, as seen in Figs. II, III, and IV, thereby

providing spaces for the reception of the ears 9 projecting from the thill coupling member 10 attached to and carried by the axle, or other fixed part of the vehicle, and for which no invention *per se* is herein claimed. The coupling eye 3 of the reinforcing iron 2 occupies a position between the ears 9, and the coupling eyes 3 and 7 are all united by a coupling bolt 9' that extends through the bolt holes in said eyes and through said ears, as seen in Fig. III.

The reinforcing and coupling irons 2 and 5 are firmly connected to each other and to the thill heel by a plurality of bolts 11 that extend through these parts, as seen in Figs. I and II, and serve to bind them firmly together.

12 designates a stay or resistance rod that extends from a point near the upper end of the heel 1 to a point near the lower end of said heel and is secured at its ends by attachment to the upper and lowermost bolts 11.

As will be readily appreciated, the two reinforcing irons 2 and 5 located respectively at the front and rear of the thill heel afford a very efficient reinforcement for said heel to resist injury thereto under strain imposed upon the heel in either a forward or rearward direction.

By providing each reinforcing bar with a coupling appliance for attachment to the fixed coupling member 10, one of the irons having a coupling eye to fit between the ears of the coupling member and the other having a pair of eyes that straddle said ears, I furnish an extremely strong connection between the thill heel and the coupling member 10 which affords a marked degree of security in the thill coupling as compared with the ordinary thill coupling appliances in which but a single coupling member is carried by the thill heel.

I claim:

1. The combination with the heel of a vehicle thill, of a pair of reinforcing irons extending longitudinally of said heel, and fitted to the front and rear faces of the heel, and each of which is provided with a coupling eye adapted to be connected to a companion coupling member.

2. The combination with the heel of a vehicle thill, of irons extending longitudinally of said heel, one of said irons being provided with a coupling eye, and the other of said

irons being provided with a pair of coupling eyes straddling the eye of the first mentioned iron.

3. The combination with the heel of a vehicle thill, of a pair of reinforcing irons extending longitudinally of said heel, one of said irons being provided with a coupling eye, and the other iron being provided with side wings having coupling eyes straddling the coupling eye of the first named iron.

4. The combination with the heel of a vehicle thill, of a forward reinforcing iron and a

rear reinforcing iron extending longitudinally of said heel, said forward iron being provided with a single coupling eye, and said rear iron 15 being provided with a pair of side wings straddling said heel and having coupling eyes straddling the coupling eye of the forward iron.

PHILIP E. EBRENZ.

In the presence of—

Wm. H. SCOTT,
EDW. M. HARRINGTON.
